UNITED STATES PATENT OFFICE.

JOHN A. TOPLIFF, OF ELYRIA, OHIO, ASSIGNOR OF ONE-HALF TO GEORGE H. ELY, OF SAME PLACE.

MOLDING-MACHINE.

SPECIFICATION forming part of Letters Patent No. 236,786, dated January 18, 1881.

Application filed May 24, 1880. (No model.)

To all whom it may concern:

Be it known that I, JOHN A. TOPLIFF, a citizen of the United States, residing at Elyria, in the county of Lorain and State of Ohio, have invented a new and useful Molding-Machine for Working Wood, of which the following is a specification.

My invention relates to that class of wood-cutting machines used for cutting irregular forms in which rotating cutter-heads are used.

My improvement consists in the method employed of adjusting the position of the cutter-heads so as to produce within certain limits any desired irregularity of the surface over which they pass. I attain this object by the mechanism illustrated in the accompanying drawings, in which—

Figure 1 is a side elevation. Fig. 2 is a plan view. Fig. 3 is a detached view of the endless chain and the reels on which it works, showing, also, a side elevation of the mandrels which carry the cutter-heads and their bearings. Fig. 4 is a perspective view of the cutter-head mandrels and their bearings; also, a section of three links of the endless chain and forms. Fig. 5 is a perspective view of the same from the rear. Fig. 6 is a detached end elevation of one of the bearings. Fig. 7 is a perspective view of a detached portion of the seat in which the bearings of the cutter-head mandrels rest.

Similar letters refer to similar parts throughout the several views.

The bed-plate or table A, the legs B B, the projecting hangers C, the hangers D, and the arms E constitute the frame-work of the machine.

F represents an endless chain, which is composed of links a, which links are hinged together at their ends, so as to form, when the chain is drawn straight, a continuous unbroken surface, as seen in Figs. 1 and 3. Said chain is suspended on suitable hexagonal reels, G G', around which it is drawn, each of the faces of said reels being equal in length to the length of the links a. Upon the upper surface of the links a a raised surface is formed, as seen in Figs. 4 and 5, (marked j.) Several of these links are grouped together, and the elevated surfaces

are so curved or otherwise formed on their edges as to constitute a pattern of form such as it is desired to reproduce. Upon the rear end of the form or pattern a small spur, m, is formed, which carries the wood to be cut forward.

H H represent the cutter-head mandrels, which are secured in upright bearings b b b' b'. The lower bearings, b b, are secured within a seat, k, upon which guides c c are formed. Said guides c c are fitted to a horizontal bar, I, which is securely fastened at its ends to the frame-work, and forms a suitable way, upon which said guides may freely slide in a transverse horizontal direction, as seen in Fig. 5. Bearings b' b' are secured to the upper portion 65 of plates d d, which extend upward from seat k and slide on the rod e, which passes transversely through them and extends across the bed of the machine, the ends being fastened to the frame-work. (See Figs. 1 and 4.) The rod e is parallel to guide or way I, on which the lever-bearings slide.

Lugs f f and g g are formed on plates d d, between which spiral springs h h are secured, for the purpose of prompting the movement 75 of the bearings b b b' b' while in operation.

On the inner upper edge of bearings b' b', at a point in a line through the mandrels H H, lugs i i are formed. They are made in the form seen in Figs. 3, 4, 5, and 6, and between 80 them the endless chain passes. Their inner surfaces are curved, as seen in Figs. 4 and 5, and they are so recessed out as to only impinge upon the edges of the elevated surface of the chain which constitutes the pattern j.

The rod e is provided with a spiral spring, l, at each end, as seen in Fig. 2. These springs press the bearings up to and continually keep them in contact with the form j.

Any irregularity of the pattern within certain limits will cause the cutter-heads to so adjust themselves that they will cut the blank wood which lies on the pattern in a form exactly like the pattern, either straight, tapering, or curved on its sides.

In front of the cutter-head mandrels H H a mandrel, J, rests in suitable bearings n n. This mandrel is armed with a cutter-head, o,

which brings the wood to the desired thickness before going between the side cutters. By making pattern on links higher at one end than at the other the thickness of wood can 5 be made to taper in passing under cutter *o*.

p p' represent guides to direct the course of blanks to be cut, one of which, *p'*, is elastic, to admit the use of blanks not of uniform size.

q represents an elastic presser, which acts, 10 in connection with guides *p p'*, in properly presenting blanks to cutters.

r r are elastic rollers for keeping the blanks in place on the pattern before and after being cut by side cutters until they can be safely 15 delivered.

15 The pulleys K L M N O P Q R S and gear T constitute the means employed by which I back gear to obtain a slow movement of the chain from the driving - axle of the machine, 20 which also drives the cutter-heads at a high rate of speed.

The operation of my improvement is as follows: When the chain, in moving forward, 25 brings one of the spurs *m* at about the position indicated by *m'* in Fig. 3, the operator places upon the pattern *j*, and immediately in front of said spur, the blank to be cut. The spur carries blank forward, and it enters between guides *p p'* and under presser *q*, and 30 thence under the horizontal cutter - head on mandrel *J*, which cuts the blank to the desired thickness, either straight or tapering, corresponding with the pattern. The knives of

this cutter-head may be straight, to cut a flat surface, or of any desired irregular shape it is 35 desired to cut on upper side of blank. From this cutter-head the blank passes between side cutters, where its sides are cut to correspond with shape of pattern on the chain and of knives in cutter-heads, and from thence is delivered from the machine. When the first blank has advanced far enough to bring another spur in position at *m'* another blank is placed on chain, and so out, one following another continuously. 40

45 What I claim as new, and desire to secure by Letters Patent, is—

1. The endless chain *F*, having a raised surface, *j*, so formed as to make a pattern in the manner and for the purpose substantially as 50 described.

2. The endless chain *F*, with pattern *j*, in combination with lugs *i i*, the same being constructed in the manner and for the purpose substantially as described. 55

3. A pattern-chain having the side contour of the work to be cut, and provided with spur to hold the work, substantially as described.

4. In a wood-working machine, a carrying-chain having its sides formed to make the 60 pattern, substantially as described.

JOHN A. TOPLIFF.
